UNITED STATES PATENT OFFICE

ROLAND W. LE BEAUMONT, OF SYRACUSE, NEW YORK

LABEL HOLDER

Application filed October 18, 1929. Serial No. 400,561.

This invention relates to improvements in label holders to be used in connection with shelves, storage bins and the like, where articles of merchandise are to be kept in storage or on display.

The main objects of the invention are to provide an improved label or card holder; to provide a holder which is inexpensive, one which will permit the label to be quickly and easily placed therein and to be removed therefrom; to firmly hold the label against the accidental displacement thereof; to permit the positioning of the label at any desired location along the holder and to be an ornament to the shelving or bin or any other receptacle used for containing merchandise, to which the label holder is attached.

In carrying out the above objects, I have provided a label holder which may be constructed of wood or metal, formed or shaped into molding of any desired design and which may be cut into desired lengths and secured to the outer edge of shelves or other suitable receptacles for containing goods which may be used in stores, warehouses, libraries and the like. Said molding being provided with a pair of opposed parallel sunk fillets or grooves extending lengthwise thereof for receiving the ends of the cards or labels used to designate the price, nature or character of the objects being stored.

Other objects relate to the form and relation of the parts thereof, all of which will more fully appear from the following description taken in connection with the accompanying drawing, in which:

Figure 1 is a perspective view of a portion of a shelving construction having the proposed label holder secured to the longitudinal front edge of the shelves.

Figure 2 is an enlarged face view of a portion of the label holder showing one of the labels in place.

Figure 3 is a vertical transverse sectional view taken on line 3-3, Figure 2.

Figure 4 is a face view of a label or card which is particularly adapted to be used with this label holder.

As illustrated in Figures 2 and 3 of the drawings, the label holder consists of a strip of molding —1— composed of wood although the molding may be constructed from metal or from any other suitable material. The molding —1— may be of any desired design for ornamenting the front edge of the shelves as —2—, to which said molding is secured.

The shelves may be supported in any suitable manner and the molding is secured to the front longitudinal edges of the shelves by any suitable means as by screws —3—. The molding extends longitudinally across the front face of the shelf and preferably with the upper edge of the molding in the plane of the top surface of the shelf —2—, thereby providing a smooth flat surface across the top of the molding and shelf so that the molding will not interfere with the placing of the goods on the shelves or the removal of said goods therefrom, as clearly illustrated in Figure 3.

The molding —1— is provided with a pair of opposed parallel sunk fillets or grooves —4— cut or molded in the front vertical surface thereof and extending lengthwise throughout the length of the molding. The grooves may, as illustrated, be positioned near the upper and lower edges of the molding —1— and have their outer side walls —5— undercut for receiving the respective sides of a card or label as —6— and securely maintaining said label in its placed position.

The card or label —6— may be of any desired length depending upon the amount of information it is required to be placed thereon and they are of slightly greater width than the distance between the outer edges —5— of the grooves —4— so that when the label is in place, the central portion of the label will be slightly bowed outwardly and,

therefore, exert a certain amount of end thrust to maintain the edges of the label against the undercut walls of the grooves and thereby prevent the accidental displacement of the label.

The labels or cards may be constructed from any desirable resilient material such as cardboard or thin sheet metal and may have the upper and lower edges —7— and 10 —8— thereof serrated so that when the label is positioned in the holder, the serrations will engage the side wall of the respective groove and prevent the label from being easily moved longitudinally along the molding.

15 The label may be quickly and easily inserted by first placing one serrated edge against the undercut wall of one of the grooves and then by pressing the opposite side inwardly, the label may be bowed outwardly at the central portion thereof until 20 the side can be inserted in the other groove, whereupon the serrated edges of the label will engage the respective undercut side wall and the label is thereby securely held in place. 25 In order to remove the label, it is only necessary to grip opposite ends of the label at the slightly bowed center thereof between the thumb and second finger and by pressing with the first finger against the upper edge 30 of the label, the label may then be readily withdrawn from the grooves.

It is evident from the foregoing description that the label holder may be provided at comparatively little additional expense as 35 the grooves —4— may be provided in any molding which it may be desired to use for finishing the front edges of the shelves or other means for supporting the articles of merchandise.

40 The cards or labels may also be constructed of various sizes and shapes and, therefore, I do not wish to be limited to the exact construction shown, as various changes may readily be made without departing from the spirit 45 of the invention, as set forth in the appended claims.

I claim:

1. A label holder of the class described, comprising, in combination a body member 50 having a pair of opposed parallel grooves sunk at substantially right angles to the face of said body member and extending longitudinally thereof, said grooves having their outer walls undercut and a resilient label 55 member having opposite sides thereof serrated and adapted to engage the undercut walls of the grooves for removably confining the label therebetween.

2. A label holder of the class described 60 comprising in combination a body member having a pair of opposed parallel grooves sunk at substantially right angles to the face of said member, the outer walls of said grooves extending inwardly from the surface 65 of the holder to the bottoms of the

grooves in diverging planes, and an outwardly arched resilient label member having opposite end portions fulcrumed on the inner edges of respective grooves with their outer edge portions held thereby in contact with 70 the outer diverging walls of respective grooves.

In witness whereof I have hereunto set my hand this 16 day of October, 1929.

ROLAND W. LE BEAUMONT.
